UNITED STATES PATENT OFFICE

2,144,278

ROASTING GRID

James Wallace, Los Angeles, Calif.

Application February 7, 1938, Serial No. 189,228

7 Claims. (Cl. 53—5)

and 11, also formed of wire, each frame being provided with a plurality of cross wires 12 to form a support for the articles being roasted.

The end portions of frame 5 are provided with socket seats 13 and 14 secured to the oppositely disposed end portions of sections 8 and 9 of the frame 5 for receiving removable rods 15 adapted to support the leaves 10 and 11 in a plurality of adjusted angular positions, this angular disposition of the leaves being rendered possible as the rod 6 to which the said leaves are pivoted is disposed below the plane of the frame 5. When the leaves are disposed in substantially the same plane as the wire frame 5, they will serve as a broiler grid for steaks, chops, and the like. It will be seen that when roasting poultry, such as turkeys, chickens and the like, the leaves are disposed at an angle to each other, forming a V-shaped supporting bottom for the food.

The roasting grid 5 is adapted for removable placement in the oven 16, of a cooking range 17, the side walls of the oven being provided with the usual slide guideways 18.

In Fig. 3 of the drawing I have illustrated the method of placement of a turkey or similar fowl 20 on the grid, the breast portion 19 being placed downwardly and resting in the angle formed by the grid leaves.

In preparing a fowl for roasting, the skin is tightly tied around the neck, and the legs and wings are trussed in the usual manner, the opening into the fowl through which the dressing is introduced being sewed to completely close the same. Preferably, the fowl's skin is then rubbed with olive oil or butter to effectually seal the pores of the skin, in order to render the same impervious to moisture.

During the roasting process, it will be apparent that the natural juices of the fowl will be directed downwardly towards the breast portions, maintaining the same at all times in a moist condition, which is greatly desired in a roasted fowl or other roasted food products.

Further, as the juices are sealed within the fowl during roasting very little will escape therefrom, and for that reason no basting of the fowl will be found necessary.

When roasting an unusually large fowl, such as a large "tom" turkey, the leaf adjusting and supporting rods 15 may be placed in the outermost oppositely disposed sockets 13 and 14, as shown in dotted lines in Fig. 3.

I claim:

1. A device of the class described comprising a wire frame member, a centrally disposed pivot

Pivots mounted on the rod 6 in any suitable manner are a pair of food supporting leaves 10

55

rod secured thereto, and a pair of food supporting leaves pivotally secured to said pivot rod.

2. A device of the class described comprising a wire frame member, a centrally disposed pivot rod secured thereto, a pair of food supporting leaves pivotally secured to the pivot rod at their oppositely disposed edges, and means to adjust the leaves towards or away from each other.

3. A device of the class described comprising a wire frame member, means to adjust said frame laterally, and a pair of food supporting leaves pivotally mounted on said frame.

4. A device of the class described comprising a substantially rectangular wire frame member formed into two parts for lateral adjustment, a pivot rod connecting said members, a pair of food supporting leaves pivotally secured to said pivot rod, and means to adjust said leaves towards or away from each other.

5. A device of the class described comprising a rectangular wire frame member divided into two parts, means to adjustably secure said parts together including a pivot rod, a pair of wire

frame food supporting leaves pivotally secured to said pivot rod, and means mounted on said frame for adjusting said leaves to or from each other.

6. A device of the class described comprising a substantially rectangular wire frame formed into two parts, a centrally disposed pivot rod connecting said frame parts, said parts being adjustable to and from each other, a pair of wire frames forming a bottom for said frame, the oppositely disposed edges of said frames being pivoted to the pivot rod, and means to angularly adjust said frames to and away from each other.

7. A roasting grid construction comprising a frame member, a pair of opposed food supporting leaves pivotally secured to said frame member, said leaves adapted to be adjusted towards and away from each other in angular relation to form a substantially V shaped food support, and means to hold said leaves in their adjusted angular positions.

JAMES WALLACE.
